[57] CLAIM

The ornamental design for a speaker housing, as shown and described.

DESCRIPTION

FIG. 1 is a top, front, right side perspective view of a speaker housing, showing our new design;

FIG. 2 is a left side elevational view thereof;

FIG. 3 is a bottom plan view thereof; and,

FIG. 4 is a rear elevational view thereof.

The broken line showing of the controls is for illustrative purposes only and forms no part of the claimed design.

FIG. 1

FIG. 2

FIG. 3

FIG. 4
